Primary Examiner — Philip S Hyder*Assistant Examiner* — Cary M Robinson(74) Attorney, Agent, or Firm — Husch Blackwell LLP(57) CLAIM

The ornamental design for a display with computer icon, as shown and described.

DESCRIPTION

FIG. 1 is a front view of a display with a computer icon. FIG. 2 is a front view of a second embodiment of a display with a computer icon; and, FIG. 3 is a front view of a third embodiment of a display with a computer icon. The broken line in the figures illustrates the display and forms no part of the claimed design.

1 Claim, 3 Drawing Sheets(56)
